UNITED STATES PATENT OFFICE.

JULIUS L. CABLE, OF BOSTON, MASSACHUSETTS, ASSIGNOR TO THE CABLE CORPORATION, OF BOSTON, MASSACHUSETTS, A CORPORATION OF MASSACHUSETTS.

FOLDING COT.

Application filed February 16, 1926. Serial No. 88,566.

This invention relates to folding cots of the general type shown in my Patent 1,507,906, in which the frame and legs are formed from semi-tubular metal, and the legs are 5 pivotally connected to the side bars to permit them to be folded in parallel relation thereto.

In cots of this type some means is necessarily provided to lock the legs in position 10 of use at right angles to the side bars, the means which has been most generally employed being various forms of folding braces, many of which, while they perform their intended function, are unsatisfactory for 15 various reasons, in that they are liable to permit the leg to collapse, under some conditions of use, and do not hold the leg in position of use with the desired rigidity and security.

20 The objects of my invention are to provide means for locking the folding legs of a device of this character which will be positive and secure, so that all possibility that the legs will be permitted to collapse will be 25 avoided. Also to provide a locking means in which the use of all forms of folding braces will be avoided, and which enables a construction to be produced which is of 30 simple and attractive appearance, and enables a reduction in manufacturing costs as compared with the common type of folding brace.

A further object is to combine the top 35 or bed of the cot with the leg locking means in such a manner that weight on the top acts to increase the effectiveness with which the legs are locked.

I accomplish these objects in the manner hereinafter described and as illustrated in 40 the accompanying drawings in which:

Fig. 1 is a plan view of a folding cot embodying my invention.

Fig. 2 is a side elevation of a portion thereof.

Fig. 3 is an end view.

Fig. 4 is a perspective view of a portion of one corner of the frame.

Figs. 5 and 6 are detail sectional views of the leg and side rail connections.

50 Fig. 7 is a detail sectional view of one of the side rails.

In general construction and arrangement the cot illustrated is similar to that shown in my said prior patent, comprising two 55 pairs of side bars 1, and three pairs of piv-

totally connected crossed legs 2, one pair being arranged in the middle, and the other pairs at the ends. The form of joint between the legs and side bars illustrated is practically identical to that disclosed in my 60 pending application filed August 6, 1925, Serial Number 48,621, and comprises a pair of head sections 3 which are riveted to the upper end of the leg and form a cylindrically shaped T-head, which is disposed between the sides of the side bar and pivotally connected thereto by a pivot pin 4 at one end. The end portions of the side bars are shaped in a U-form in cross-section, and, between their end portions, their side portions 70 are drawn inward so as to form a relatively narrow slot 5, as shown in Fig. 7, and the canvas top, or bed 6 is extended between opposite bars over the upper sides thereof, about their outer sides and thru the slot 5 75 of each bar, and then about a cord 7, of substantially greater diameter than the slot, so that the top is securely attached to the bars thereby. The portions of the canvas which comes opposite the end portions of the bars 80 is cut away and the cord is discontinued at these points. In practice, the canvas is not applied to the frame until after the metal work and the canvas top have been finished, the cord being held in the top by stitching. 85 In applying the top to the frame one end of the top is slid into one pair of bars from their middle ends and drawn along therein to the opposite ends thereof, until it is in position and then the opposite end of the 90 top is drawn into the other pair of bars in like manner, until the whole top is in the position shown in Fig. 1. The cord prevents the withdrawal of the top from within the side bars by strain thereon transversely of 95 the bars, the pull on the cord being somewhat relieved by the half turn of the canvas about the bar.

For the purpose of providing means for locking the legs in their position of use, or 100 unfolded position at right angles to the bars, a stud 8, having a head 8', is rigidly mounted in the middle line of the T-head 3 of each corner leg, the stud extending perpendicularly to the top side of the T-head, and being 105 located adjacent the end of the head nearest the end of the bar to which it is pivoted, the pivot 4 being located at the opposite end of the T-head and the end portion of the side bar extending for a substantial distance be- 110

yond the opposite end of the T-head from the pivot. Said side bar end-portion is provided with an aperture 9 thru which the stud 8 passes when the leg is swung up to the right angular position in which the top portion of the head thereon engages the inner or underside of the side bar, in which position the stud 8 projects above the bar to such an extent that there is a space of substantial width between the under side of the head 8' and the top surface of the bar. A locking slide 10 is slidably mounted on the end portion of each side bar, said slides being similarly shaped and held thereon in corresponding relation. A pin 11 is mounted in the sides of each slide and extends thru an inclined slot 12 in each side of the side bar. Each slide is also provided with a notch 13 in the middle of its inner end in position to receive the stud 8, so that the stem of the stud will be located in the slot and the head of the stud will rest on the slide at each side of its notch. The slots 12 are inclined upward from the ends of the side bars, so that, in locking the leg in position of use, the slide is pushed inward until its notch 12 receives the stud 8, and, as it is pushed inward, it is forced upward by reason of the inclination of the slots 12, thereby acting to draw the stud 8 upward, so as to draw the T-head 3 firmly against the under side of the side bar. The slides 10 are formed to extend beyond the ends of the side bars to a substantial extent and each side of the extended portion thereof is provided with a strap aperture 14. A strap 15 is secured in each end of the canvas top 6 and extends the entire width thereof and beyond the side edges, and each end portion of the strap is passed over the adjacent slide and back thru the apertures 14 thereof, and then drawn tight and secured by means of a buckle 16 on the under side of the top.

By this arrangement the end portions of the canvas are supported at the level of the other portions thereof and, at the same time, when the weight of a person is being supported by the canvas there will be tendency to draw the same from each end towards the middle, so that not only is any tendency resisted for the slides to move in a direction to unlock the legs, but there is also a tendency to force the slides in a direction to lock the legs more securely and to draw the

T-heads thereon more firmly against the under sides of the side bars, thus forcing the legs into their right angular position, in case it should happen that the slide had not been forced inward to its fullest extent when the cot was set up. As the locking slides for the legs appear as continuations of the side-bars, and use of braces is avoided, the appearance of the cot, when set up, is improved. 55

I claim:

1. A folding cot comprising a side bar having a semi-tubular end portion with its open side facing downward, and having an opening therein, a leg having a T-head adapted to fit in said end portion and pivotally connected at one end thereto, to permit the top portion of the head to be swung into engagement with the underside of the bar, a stud rigidly mounted in the top of said head remote from its pivot and arranged to extend thru said opening when the head is in engaged position, a semi-tubular locking slide fitted on said side bar, the latter having oppositely disposed slots in the side of its end portions arranged to incline upward as they extend towards the said opening therein, a pin mounted in the sides of said slide and extending thru said slots and means in the upper end of said stud arranged to be engaged by said slide to lock said T-head in engaged position. 65

2. A folding cot comprising side bars having a textile top connected thereto, a leg at the end of each side bar having a T-head at its upper end, each T-head having a pivotal connection at one end with the side bar, to permit the top portion of the bar to be swung into engagement with the underside of the bar to which it is pivoted, a stud rigidly mounted in each head remote from its pivot and means permitting the same to extend thru its bar when its T-head is in engaging position, and a slide mounted on the end portion of each bar for movement longitudinally thereof arranged to engage said stud to lock the T-head in engaging position and having a connection with the adjacent end portion of the top in such a position that strain on the top from each end towards the middle tends to hold the slides in locking engagements with their respective studs. 70 75 80 85 90 95 100 105

In testimony whereof, I have signed my name to this specification.

JULIUS L. CABLE.
